UNITED STATES PATENT OFFICE

SAMUEL K. SHUSTER, OF SANDYVILLE, OHIO, ASSIGNOR OF ONE-HALF TO IRA B. SHUSTER, OF LOUISVILLE, OHIO

PROTECTIVE SHOOTING MECHANISM

Application filed May 7, 1931. Serial No. 535,613.

My invention relates to shooting devices for protection against robbery and holdups, and more particularly to mechanism for rapidly firing a number of shots within a given 5 area at a desired location, and controlled from a remote point.

The improved apparatus to which the invention relates is particularly applicable to banks for providing adequate protection in 10 case of a holdup, at which time it is desirable to direct a fusillade of shots at one or more of the robbers without endangering the lives of other persons in the bank at the time.

In the past such devices have been placed 15 in a convenient location in the wall, as for instance adjacent a teller's window, and have functioned to fire a series of shots calculated to strike the body of a robber standing in front of the window. In these devices, if 20 the shots are all directed along the same path, the chances are very great that the robber might not stand in the line of the shots, and thus escape injury.

Attempts have been made to provide for 25 firing a series of shots in such a way as to distribute them over a given area, but in such instances a plurality of firing mechanisms directing shots in slightly different directions are required; or a moving barrel sweeping 30 across a lateral path, similar to the modern machine gun, must be provided. Such attempts result in complicated and expensive mechanisms, difficult to manufacture and install, and requiring skill in maintaining them 35 in proper adjustment and working order.

All of these prior devices have proven unsatisfactory and undesirable because of the low degree of safety attendant upon their 40 operation, since the lives of any persons in the bank at the time of the holdup are in grave danger, due to the substantially horizontal paths traveled by the bullets, which paths take in a considerable area in the bank.

It is an object of the present invention to 45 provide a simple and compact cartridge firing mechanism adapted to be located in a bank and the like, and operated from a remote point of control to fire a series of shots substantially uniformly distributed over a 50 desired area.

Another object is to provide an overhead cartridge firing apparatus adapted to fire a series of shots downwardly to be substantially uniformly distributed over a given area, means being provided for varying the timing 55 of the firing so as to fire the shots in rapid succession or a plurality thereof simultaneously.

Another object of the invention is to provide a single cartridge firing mechanism 60 which will distribute a series of shots substantially uniformly over a given area, which mechanism is inexpensive to manufacture, easy to install and operate, and requires no fine adjustments of parts to insure satisfactory performance; and which provides for a high degree of safety while affording ample protection against robberies and holdups. 65

These and other objects are attained by the improved apparatus comprising the present invention, which may be stated in general terms as including a vertically disposed cartridge magazine having a plurality of cartridge chambers disposed preferably in different angular directions, hammer means 70 for firing one or more of the cartridges located in said chambers, means for intermittently rotating said magazine to bring successive cartridges under the hammer means, timing means cooperatively associated with said magazine rotating means for selectively actuating said hammer means as the successive cartridges are moved into registry therewith, means for adjusting the timing means to fire the cartridges singly in 75 rapid succession or a plurality thereof simultaneously, and remote control means for operating the magazine rotating means. 80

A preferred embodiment of the present improvements is illustrated in the accompanying drawings, in which 85

Figure 1 is a partially diagrammatic view showing the improved shooting apparatus mounted above a robber standing in front of a teller's window in a bank, the paths taken 90 by the shots being represented in dot-dash lines;

Fig. 2 is a plan sectional view taken substantially on line 2-2, Fig. 1, showing how the shots are distributed; 100

Fig. 3 is a side elevation of the shooting mechanism mounted in a chandelier, parts of the latter being omitted for the sake of clearness;

5 Fig. 4 is a plan sectional view as on line 4—4, Fig. 3, distant parts being removed; and

Fig. 5 is a detached sectional view of the improved cartridge magazine.

10 Similar numerals refer to similar parts throughout the several views.

The invention is adapted to be placed in a convenient overhead location in a bank and the like, so that the shots fired by the mechanism will be directed substantially vertically downward toward the area likely to be occupied by a robber or holdup man. In the drawings the shooting mechanism is shown conveniently mounted in an overhead chandelier.

The chandelier indicated generally at 10 is hung from the ceiling in the usual manner as by chain 11, and may be located above and in front of a teller's window represented at 12 in a bank and the like.

15 The improved shooting apparatus is concealed within the chandelier and is preferably enclosed in a housing 13. The shooting apparatus is adapted to be controlled by one or more switches 14 located at remote points and electrically connected thereto by conductors W, and is adapted to fire a series of shots downwardly upon a robber 15, standing in front of the window. The shots travel in paths indicated by the dot-dash lines 16 in Fig. 1, and are distributed substantially uniformly over the area occupied by the robber, as best shown by the points 16' in Fig. 2, in a manner to be described in detail.

20 The improved shooting mechanism illustrated in detail in Figs. 3, 4, and 5, includes a frame 17 mounted within the chandelier 10 and supported upon the bottom plate 18 thereof. The plate 18 is provided with an aperture 19, preferably at its central portion, through which the shots are directed.

25 A shaft 20 is positioned above the aperture 19 and preferably axially alined therewith, the ends of the shaft being secured to the frame 17 by brackets 21. Rotatably mounted on the shaft and coaxial therewith is the cartridge magazine 22 having a plurality of circumferentially located cartridge chambers 23 therein directed toward the aperture 19. These chambers are inclined in slightly different directions relative to each other, and at slight angles to the vertical as indicated in Fig. 5, and are normally loaded with cartridges 24.

30 A magazine cover plate 25 is fixed upon the shaft 20 and spaced slightly above the magazine 22 so as to allow free rotation of the latter when it is loaded with cartridges. This cover plate is preferably provided with a per-

ipheral notch 26 for permitting reloading of the magazine, and with one or more firing pin apertures alined with the circumferential axis of the cartridge chambers. In the drawings two diametrically opposite firing pins 27a and 27b are shown. The firing pins 27a and 27b are normally held in slightly raised position above the cartridges 24 by resilient members 28a and 28b respectively, which are secured to the cover plate 25.

35 Means for intermittently rotating the magazine 22 may include a vertically disposed shaft 29 preferably parallel with and laterally spaced from shaft 20, a motor 30 operatively connected to the upper end of the shaft, and crank and lever means operatively connected between the lower end of the shaft 29 and the magazine 22 for transmitting the rotation of the shaft to the magazine for intermittently rotating the latter.

40 The motor 30 may be mounted upon the frame 17 and is preferably provided with a worm 31 upon its motor shaft, which is adapted to mesh with a worm gear 32 fixed upon the upper end of the shaft 29 to rotate the shaft.

45 The shaft 29 may be rotatably mounted upon the frame 17 in any convenient manner, and is shown journaled in brackets 33 which are secured to the frame. A disk 34 may be secured upon the lower end of the shaft 29, and a crank or pitman arm 35 is connected at one end eccentrically with the disk 34 as at 36. The other end of the pitman 35 is pivotally connected to a lever arm 37 intermediate its ends, as at 38. The arm 37 is pivotally connected at one end to a bracket 39 secured to the frame, and pivotally connected at its other end to a ratchet pawl 40. The other end of the ratchet pawl 40 has a notched portion 41 formed thereon which is adapted to successively engage ratchet teeth 42 formed upon the outer cylindric surface of the magazine 22. A spring 43 normally urges the notched portion 41 into engagement with the teeth 42.

50 Thus when the shaft 29 is rotated by the motor 30 the pitman 35 will oscillate the lever arm 37 to cause the ratchet arm 40 to successively engage the teeth 42 and intermittently rotate the magazine 22.

55 A circular plate 44 may be mounted upon the underside of the magazine 22 and is provided with a series of circumferentially arranged depressions 45 which are adapted to be successively engaged by the resilient latch member 46 as the magazine is rotated. This latch member functions to hold the magazine stationary as the ratchet arm 40 moves to the right as viewed in Fig. 3 to engage the next succeeding tooth 42.

60 Means for striking the hammers 27a and 27b to selectively fire the cartridges moved thereunder may include hammer rods 47a and 47b respectively, which are journaled upon

the frame in brackets 48, 49a and 49b. The rods 47a and 47b are provided at one end with angularly bent portions 50a and 50b which have hammer portions 51a and 51b at their ends arranged to strike the firing pins 27a and 27b respectively, when the rods are rotated axially in their brackets. Springs 52a and 52b are provided upon the rods 47a and 47b respectively, for normally urging the hammer portions toward the respective firing pins.

The opposite ends of the rods 47a and 47b have formed thereon angularly bent cam-engaging portions 53a and 53b, which portions are engaged by cam wheels 54a and 54b respectively, secured upon shaft 29. As the cam wheels are rotated, they raise the respective end portions 53a and 53b to axially rotate the rods 47a and 47b and raise the respective hammer portions 51a and 51b upwardly away from the firing pins. When the end portions 53a and 53b drop over the high points of the cams, the springs 52a and 52b cause the hammer portions to strike the firing pins and fire the cartridges positioned thereunder.

The action of the hammer portions is timed by the cams so that the firing pins are struck by the hammers when the magazine 22 is stationary. Thus when two cartridges are fired the magazine will be rotated by the ratchet pawl 40 through a partial rotation sufficient to bring the next successive cartridges under the firing pin, and the action is repeatedly continued until all of the cartridges in the magazine have been discharged.

The cam wheels 54a and 54b are locked in position upon the shaft 29 by means of lock nuts 55 screwed upon the threaded portion 56 of the shaft. Thus it will be seen that by loosening the lock nuts the cams may be adjusted relative to each other so as to cause the hammers 51a and 51b to fire the firing pins 27a and 27b simultaneously. Obviously, by increasing the number of cams and corresponding hammer and firing means, any number of the cartridges may be fired simultaneously.

In operation, if a robber attempts to hold up a bank by pointing a gun at a teller while standing in front of the teller's window; as soon as he occupies a position directly under the chandelier 10, any authorized person in the bank observing the situation may throw one of the switches 14 to immediately fire a series of shots downwardly upon the person of the robber. Any number of the devices may be placed above the tellers' windows to insure adequate protection, and the switches 14 may be located within easy reach of bank guards when ordered to throw up their hands by the robber or his accomplices.

In reloading the magazine the same may be rotated manually to permit successively

inserting new cartridges through the notch 26, without any danger of operating the firing mechanism, since the teeth 42 will easily slip under the ratchet arm 40 without moving the shaft 29. It will be seen that when the improved shooting mechanism is operated a plurality of shots will be distributed substantially uniformly, as shown by the points 16' in Fig. 2, over a given area calculated to take in the body of the robber standing in front of the teller's window, and that the lives of other persons in the bank at the time of the holdup are not endangered since the shots are fired downwardly.

The adjustability of the hammer actuating cams relative to each other, together with the angularity of the cartridge chambers provides for instantaneous and efficient protection against one or a number of robbers, and renders the device adaptable to any and all conditions.

I claim:

1. In a cartridge firing mechanism adapted to be located overhead in a bank and the like, a vertically disposed cartridge magazine having a plurality of cartridge chambers, cartridges in said chambers, hammer means for firing a plurality of the cartridges, means for intermittently rotating said magazine to bring successive cartridges under the hammer means, timing means cooperatively associated with said magazine rotating means for selectively actuating said hammer means as successive cartridges are moved thereunder, means for adjusting the timing means to vary the sequence of firing of the cartridges, and remote control means for operating the magazine rotating means.

2. In a cartridge firing mechanism adapted to be located overhead in a bank and the like, a vertically disposed cartridge magazine, having a plurality of cartridge chambers disposed in different angular directions calculated to distribute shots over a given area, cartridges in said chambers, hammer means for firing one of the cartridges, means for intermittently rotating the magazine to bring successive cartridges under the hammer means, timing means cooperatively associated with said magazine rotating means for actuating said hammer means as successive cartridges are moved thereunder, and remote control means for operating the magazine rotating means.

3. In a cartridge firing mechanism adapted to be located overhead in a bank and the like, a vertically disposed cartridge magazine having a plurality of cartridge chambers disposed in different angular directions calculated to distribute shots over a given area, cartridges in said chambers, hammer means for firing a plurality of the cartridges, means for intermittently rotating said magazine to bring successive cartridges under the hammer means, timing means cooperatively asso-

ciated with said magazine rotating means for selectively actuating said hammer means as successive cartridges are moved thereunder, means for adjusting the timing means to 5 vary the sequence of firing of the cartridges, and remote control means for operating the magazine rotating means.

4. Cartridge firing apparatus including a frame, a magazine rotatably mounted on 10 the frame and having a plurality of cartridge chambers, ratchet teeth on the outer periphery of the magazine, a ratchet arm arranged to engage said teeth for rotating the magazine, a shaft rotatably mounted on the frame, 15 means for driving the shaft, a disk fixed on the shaft, a pitman arm operatively connected between the disk and the ratchet arm for intermittently rotating the magazine, hammer means arranged to strike one of the cartridges in the cartridge chambers for firing 20 the same, and cam means on the shaft for actuating the hammer means.

5. Cartridge firing apparatus including a frame, a magazine rotatably mounted on the 25 frame and having a plurality of cartridge chambers disposed in different angular directions calculated to distribute shots over a given area, hammer means adapted for firing cartridges in said cartridge chambers, a 30 shaft, means for driving the shaft, ratchet means operatively connected between the shaft and magazine for intermittently rotating the magazine, and cam means on the shaft for selectively actuating the hammer 35 means as the cartridge chambers are moved into registry therewith.

6. Cartridge firing apparatus including a frame, a magazine rotatably mounted on the frame and having a plurality of cartridge 40 chambers, hammer means adapted for firing a plurality of cartridges in said chambers, a shaft, means for driving the shaft, ratchet means operatively connected between the shaft and magazine for intermittently rotat- 45 ing the magazine, and cam means on the shaft for selectively actuating the hammer means as the cartridge chambers are moved into reg- 50 istry therewith, said cam means being adjustable relative to each other for varying the timing of the firing of the cartridges.

7. Cartridge firing apparatus including a frame, a magazine rotatably mounted on the frame and having a plurality of cartridge chambers, ratchet teeth on the outer periph- 55 ery of the magazine, a ratchet arm arranged to engage said teeth for rotating the magazine, a shaft rotatably mounted on the frame, means for driving the shaft, a disk on the shaft, a pitman arm operatively connected 60 between the disk and the ratchet arm for intermittently rotating the magazine, a plu- 65 rality of hammers each adapted for firing one of the cartridges located in said magazine, a plurality of cams on the shaft each adapted to actuate one of the hammers for successive-

ly firing cartridges as the chambers are moved thereunder, and means for adjusting the cams relative to each other for varying the timing of the firing.

In testimony that I claim the above, I 70 have hereunto subscribed my name.

SAMUEL K. SHUSTER.
